ARTIFICIAL HAND

John Sargeson, Long Branch, Ontario, Canada

Application October 31, 1952, Serial No. 317,917

16 Claims. (Cl. 3—12.6)

1

The present invention is directed to artificial limbs and the like, and particularly to an artifice whereby a mechanism simulates the functions, at least in part, which characterize a normal human hand.

It is known to provide a member which can be attached to a fragment of a fore-arm above and/or below the elbow and which my mechanical devices associated therewith endeavours to provide means for grasping and holding articles.

Notable among such agencies is the invention described and defined in my co-pending application Serial No. 258,585, filed November 28, 1951.

In the above-named application, the invention comprises an artificial hand whereof two jaw-like members can be made to open and close to grasp and hold an article and wherein control of the action is centred in a reel-like agency having a ratchet and escapement actuated by some other body member, such as a foot. The initial pre-setting of the jaw positions and the principal opening effort is effected by the bending of a member such as a knee while the reel is locked by a predetermined movement of a foot. When it is desired to release the jaws, a designated motion of the said foot engages the ratchet and locks the reel, thus allowing a control agency associated therewith to exert a pull on the movable jaw in an opening direction.

Whereas this above noted construction is very satisfactory for use by persons having full use of a given leg or foot member, or of another arm member, there are many "amputation cases" wherein such members are also either missing in part or incapacitated. In a further aspect, there are occupations which require a disabled person to use the remaining active and/or normal members in such a way as to make them unavailable for the purpose of controlling an artificial member. Although not limited to any special case, it is to these latter cases that the present invention is especially directed, but in every sense the invention should be regarded as a further refinement and improvement in the above-mentioned construction.

In its broad aspect the invention contemplates an articulated supporting structure, a pair of co-acting jaws mounted on a lower part of the said structure and of which at least one jaw member is arranged to hinge thereon to provide opening and closing movements, a resilient means normally urging the said jaws to adopt a predetermined attitude, a flexible element connected to a said movable jaw to provide a controllable change in the said predetermined attitude, a

5 spring tensioned reel associated with said flexible element for unwinding and winding a portion thereof, means for supporting the said reel upon an upper portion of said supporting structure, 10 ratchet means for said reel, means extending outwardly and adjustable in a direction effectively normal to the average attitude of the axis of the upper portion of the said supporting structure for actuating said ratchet to lock and unlock said reel in respect of its tendency to rotate about its axis, means actuated by a human agency for altering the angular relation between the respective axes of the upper and lower portions of said articulated supporting structure, means for locking said movable jaw in the said changed predetermined attitude and means controlled by a human intelligence for unlocking said last named locking means.

20 In a practical embodiment of these teachings, the upper portion of the articulated supporting member may be fastened to the upper arm of the subject limb and the lower portion to a fragmentary fore-arm thereof, the active elbow joint being controlled by human intelligence to articulate 25 the said member and change the axial angle of the system in a predetermined manner.

In a further aspect, the means for actuating the ratchet comprises an extended lever arrangement which is tensioned to maintain the ratchet 30 in a predetermined condition and wherein by pressing one element of this lever arrangement against the body of the subject, the ratchet is caused to assume a predetermined second position so long as such pressure is maintained.

35 In another aspect, the means for locking the movable jaw in its changed predetermined position may take the form of a second ratchet and reel mechanism spring loaded in one position and cord actuated in the other, or it may conveniently 40 take the form of a jam-lock operating upon the flexible element to hold or release it under control of a lanyard actuated by the intelligent movement of a designated human muscle system, such as a shoulder joint.

45 These generalized teachings will now be more intimately elucidated by contemplation of a practical embodiment of construction described with reference to the accompanying drawings wherein:

Fig. 1 shows more or less pictorially an artificial hand system in accordance with the invention.

Fig. 2 depicts a part of Fig. 1 with the members arranged in a different attitude.

Fig. 3 depicts the invention in another attitude of use.

Fig. 4 is a side view of the artificial hand detached from the limb of the wearer.

Fig. 5 is a further side view but at right angles to Fig. 4.

Fig. 6 depicts a section along the lines 6—6 of Fig. 7.

Fig. 7 is a sectioned view of the jaw end of the structure showing the jaws in an open position.

Figs. 8 and 9 are sectionized views detailing the tilting and jamming plate mechanism, one view being taken at right angles to the other.

Fig. 10 shows somewhat schematically a convenient method of adjustably anchoring the fixed end of a flexible control element, and

Fig. 11 depicts a portion of the jam-lock mechanism.

Referring now to these figures, human upper arm 1 and fragmentary forearm 2 bendable at elbow 3 (Fig. 3) carry respectively upper support member 4 and lower member 5 articulated at 6 to yield in accordance with movements of elbow 3. Member 4 includes straps by which it is secured in usual manner; and part 2 is a known type of laced socket.

The improved structure comprises a reel assembly 7 which affords variable termination for flexible element 8 which passes through guide pulley 9 and lock mechanism 10 over pulleys 11, 12 and 13 to adjustably fixed termination 14.

Jaw assembly 15 is made up of a jaw fixedly attached to a base 15' carried by said lower body member 5. The jaw assembly 16 is made up of the movable jaw pivoted at 16' on said base 15'. Said jaws co-act to provide the main agency which simulates a hand. In practice the assemblies comprising the grasping jaws are often covered by some glove-like arrangement (not shown) to visually simulate a gloved human hand.

The spring loaded reel assembly 7 includes an escapement or ratchet wheel 18 and latch 19 which latter is spring-loaded in this example to be normally disengaged; that is, the reel is ordinarily free to turn counter-clockwise in order to pay out the flexible element 8 against the tension of a coil spring 17 by which the reel is loaded. Spring 17 urges the reel in a clockwise direction at all times.

A torsional spring 25 is employed to act on the movable jaw 16 with sufficient force to press it to a fully open position. Said movable jaw includes a flat spring element 21 which is adapted to yield when the jaws grasp an object so as to not only enable the jaws to take a firm hold but also to accommodate any slight give in the cable locking device, as hereinafter more fully detailed.

The cable 8 when pulled taut tends to close the jaw assemblies 15, 16, and spring adjusters 20, 21 bring the jaws into a firm gripping friction with any article grasped (a book is exemplified). The springs 20 and 21 thus provide a certain tolerance on the closure which avoids the necessity of providing a precise action in the jaw-locking parts of the mechanism. The jaw end of cable 8 is shown as fastened by an adjustable device comprising the spaced beads 23 and the fixed fork 14, as in my co-pending application, which provides for changing the spacing of the jaws.

Closing of the jaws is effected by a pull exerted on cable 8. This is carried out by altering the angle of the articulation of members 4 and 5 by unbending these arm parts at the elbow while holding the reel 7 from unwinding by the use of the ratchet wheel 18 and the latch or dog 19. The ratchet wheel is integral with the reel. The latch

is pivoted at 19' and is normally held disengaged by a spring 19'.

To operate the latch 19 there is provided a depressible plate 24 in the nature of a bellcrank lever pivoted at 24' on part 4 and having an arm portion connected by a link to the latch. The depressible plate is arranged at the inner side of the upper arm 1 near the shoulder so that it can easily be depressed by drawing the upper arm inwardly toward the torso, as depicted in Fig. 2.

In the disengaged position of lever 24, shown in Fig. 1, the wearer is free to move the amputated limb with the appliance on it in any manner desired and in any elbow motion the cable 8 is simply payed out by the reel 7 or wound thereon accordingly in order to take up slack and maintain it under light tension of the winding spring 17.

From inspection of Fig. 3 it will be evident that if the angle of articulation (elbow movement) is widened while the reel 7 is locked the cable 8 will be pulled, that is, tend to become longer between its terminations and since, with the reel locked it can lengthen only by taking up cable over the pulley circuit 11, 12, 13, the action of straightening out the elbow will urge the jaws to close. Spring 25 has, of course, been urging the jaws to open and the cable must be pulled with sufficient force to overcome spring 25 and to flex spring 21 in order to bring the jaws firmly together or against an object to be grasped.

It is evident from Fig. 3 that, up to this point, closing of the jaws depends jointly upon the angle of articulation of the limb parts 4, 5 and of the preset angular position at which the reel 7 is locked, and that to maintain the jaws in the "grasped" position without dependence upon those angular attitudes some additional agency must be invoked. To this end the jaw holding mechanism 10 has been devised. A favoured form of this mechanism is depicted throughout the principal figures but is more particularly elucidated in Figs. 7, 8, 9 and 11. The cable 8 is caught up at 26 and fastened to the front end of a slotted plunger 27 journalled in the base 15' for endwise movement. A cross pin 28 extends through the slotted portion of the plunger to limit its movement and a spring 28' seated against this pin presses the plunger forward, as indicated by the arrow, Fig. 8. A jam-plate 29 spring urged by coil spring 30 normally locks the plunger 27 against movement in the direction of the arrow (Fig. 8) but allows movement of the plunger in the other direction. The cable 8 and the plunger have nearly corresponding movement both in phase and amplitude and it is evident that this mechanism will lock the cable at any degree of selected tension and will hold the jaws in the corresponding predetermined gripping relation when changes in the angle of articulation of 4, 5, or changes in pre-setting of reel 7 may allow relaxing of cable 8 above point 26.

A lanyard 32 made captive to the jam-plate at 33, when pulled, will release the said jam-plate and allow the plunger to be urged downward by its spring 28' thus relaxing the whole length of cable 8, the other control agencies permitting. The lanyard desirably extends over guide-pulleys on part 4 and across the back of the wearer to the far shoulder where it is anchored in conventional manner for shoulder or other muscular actuation of a limb member.

The novel features of the invention can now be readily visualized. The wearer advances the jaws toward an object to be grasped keeping the angle of articulation between parts 4 and 5 as acute as

possible and if necessary adjusting the preset opening of the jaws 15, 16. When ready to do the actual grasping the reel is locked by moving the upper arm 1 toward the torso to depress the lever 24 and thereby induce the latch to engage the ratchet wheel 18. At the same time lanyard 32 is checked to be sure it is relaxed and the arm is then straightened thus tensing cable 8 and closing jaws 15, 16, against the desired objects. The tilting jamming plate 23 holds cable 8 in tension at its lower end thus maintaining jaws 15, 16 closed under the combined forces of tensed lower section of cable 8, and springs 29, 21, 25; the jaws now residing in a sort of cushioned "grasp" which holds against any small variations in the applied forces, as long as jam-lock 29 is not disturbed. The arm system and "hand" now firmly grasping an object may be bent or moved through a normal attitude without unlocking the jaws. When the object is to be released, a flick of the lanyard control muscle frees the jam-lock which allows the jaws to readily open under the influence of spring 25. The spring 28 co-operates to urge the plunger forwardly to aid the opening movement of the jaws.

It will be evident from inspection of the drawings that the invention embraces a compact unitary assembly which is easily fitted to persons of varying size without extensive adjustment, and can usually be attached after dressing and wholly upon the upper portion of the body. The system is light in weight and can be worn with a minimum of fatigue and discomfort. The lanyard imposes no hardship upon the wearer since it is tensed only momentarily when releasing a grasped object or when pre-setting the jaw openings.

What I claim is:

1. An artificial hand system comprising a two-part articulated supporting structure, a pair of co-acting jaws mounted on a lower part of said structure and of which at least one jaw member is arranged to hinge thereon to provide opening and closing movements, a resilient means normally urging the said jaws to adopt a predetermined attitude, a flexible element connected to the movable jaw to provide a controllable change in the said attitude, a spring tensioned reel associated with said flexible element for discretely winding and unwinding a portion thereof, means for supporting the said reel upon an upper portion of said supporting structure, ratchet means for said reel, means extending outwardly and adjustable in a direction effectively normal to the average attitude of the axis of the upper portion of said supporting structure for actuating said ratchet to lock and unlock said reel in respect of its tendency to rotate about its axis, means actuated by a human agency for altering the angular relation between the respective axes of the upper and lower portions of said articulated supporting structure, means for locking said movable jaw in the said changed predetermined attitude, and means controlled by a human intelligence for unlocking said last named locking means.

2. An artificial hand system as defined by claim 1 wherein the movable jaw support is actuated by an arrangement of pulleys co-operating with said flexible element to take up or pay out portions of said element in accordance with tensions applied to the said flexible element.

3. An artificial hand system in accordance with claim 1 wherein the said reel is tensioned to normally take up slack in the said flexible element, and is characterized by a ratchet locking device

which when closed prevents the reel from paying out any stored portion of the said flexible element.

4. An artificial hand system of the type defined by claim 1 wherein the means for actuating the reel latch comprises an arrangement of levers, an outer member of which is so positioned that when the upper arm member of the natural supporting limb is urged toward the torso 10 of the wearer the said ratchet is locked against unwinding and wherein the lever system is spring-loaded to disengage said ratchet when the said outer member of the lever arrangement is freed by swinging the said arm member away 15 from the torso.

5. An artificial hand system of the type defined by claim 1 wherein the means for locking the jaws in a predetermined position comprises a latching mechanism to which a selected point 20 on the said flexible element is maintained captive.

6. An artificial hand system of the type defined by claim 1 wherein the means for locking the jaws in a predetermined position comprises a guided plunger spring-loaded to urge it in a specified direction, means for maintaining a termination of said plunger captive to a selected point 25 on said flexible element, guide means permitting said plunger to move in either of two specified directions in correspondence with movements of said flexible element, latching means loaded to normally permit movement of said plunger only in said one direction which is opposite to that urged upon said plunger by its said spring loading, and means for disabling the load on said latch to release said plunger for motion in either 30 of said specified directions when the locking of said jaws is required to be interrupted.

7. An artificial hand system of the type defined by claim 1 wherein the means for locking the jaws in predetermined positions comprises a guided plunger spring-loaded to urge it in one 40 of two specified directions, means for maintaining said plunger captive to a selected point on said flexible element, guide means permitting said plunger to move only in the said two specified directions in correspondence with similarly phased movements of said flexible element, a jam-lock device organized to normally snub the said plunger when it attempts to move in the said one of two specified directions, spring loading means tending to retain the said jam-lock in the snubbing attitude and cable means for disabling the last mentioned spring loading means 45 when it is desired to change the locking of said jaws from one predetermined position to another.

8. An artificial hand system of the type defined by claim 1 wherein the said flexible element comprises a cable, and wherein the said cable is terminated at one end at a point on the surface of said reel and at its other end by a slotted member, the said other end of the cable being characterized by a plurality of knots arranged along a specified portion thereof and 50 which co-operate with the said slotted member to snub the cable at selected points along the said other end portion to adjust the effective total length of said flexible element in steps over a predetermined range.

9. An artificial hand comprising coacting jaws of which one is relatively movable, an articulated support for attachment to an amputated limb of the wearer, said support having an outer part and an inner part with an elbow juncture for bending movements performed at the will of the

wearer, said outer part carrying said jaws at its distal end, and means carried by said inner part for actuating said movable jaw and including a cable extending to and connected to the movable jaw, and further including a reel device utilising an unbending elbow movement of said outer part for exerting an operational pull on said cable, and releasable means on said outer part of the support for automatically locking said cable in its pulled position so as to maintain the movable jaw in the position to which it has been moved independently of said reel device.

10. An artificial hand comprising a fixed jaw, a relatively movable jaw, a support for attachment to the amputated limb of the wearer, said support having an outer part and an inner part connected at an elbow-forming juncture for bending movements to be performed at the will of the operator, said outer part carrying said jaws at its distal end, means for actuating said movable jaw including a cable connected to said movable jaw and extending to said inner part, a spring tensioned reel on said inner part and connected to said cable for winding and unwinding actions to keep the cable taut irrespective of elbow movement of said support, a ratchet device for locking said reel against unwinding so as to utilize an unbending movement of said outer part at the elbow to exert an operational pull on said cable, and releasable means carried by said outer part for securing the jaw end of said cable in pulled position.

11. A structure as set forth in claim 10, in which the cable is trained over pulleys to pull the movable jaw closed, and in which a spring presses this jaw to open position.

12. A structure as set forth in claim 10, in which the ratchet device includes a ratchet wheel movable with the reel, a dog for engaging the

teeth of the ratchet and normally held disengaged, and a member on the upper attachment part arranged to be pressed for causing engagement of said dog.

13. A structure as set forth in claim 10, in which the ratchet device includes a ratchet wheel movable with the reel, a dog for engaging the teeth of the ratchet wheel and normally held disengaged, and a lever-like plate connected to said dog and pivotally arranged on the upper attachment part at the inner side of the wearer's arm so that it can be depressed by inward movement of the arm toward the torso.

14. A structure as set forth in claim 10, in which the releasable means for the cable is of the positive type, and in which release of the cable is effected by a lanyard.

15. A structure as set forth in claim 10, in which the releasable means for the cable comprises a tilting and jamming plate.

16. A structure as set forth in claim 10, in which the releasable means for the cable comprises a plunger journaled on the socket and connected to the cable, a tilting and jamming plate movably mounted on said socket and having said plunger extending therethrough for locking it against forward travel, and a lanyard for release of said tilting and jamming plate.
